UNITED STATES PATENT OFFICE

160,635

SANITARY SHIELD FOR BOTTLES

William Lawlor, Eagle Rock, Calif.

Application May 28, 1949, Serial No. 2,926

Term of patent 3½ years

(Cl. D58—26)

To all whom it may concern:

Be it known that I, William Lawlor, a citizen of the United States, residing at Eagle Rock, in the county of Los Angeles and State of California, have invented a new, original, and ornamental Design for a Sanitary Shield for Bottles, of which the following is a specification, reference being had to the accompanying drawing, forming part thereof.

In the drawing

Fig. 1 is a side elevational view of a sanitary shield for bottles, showing my new design;

Fig. 2 is a top plan view of the device, shown in Figure 1; and

Fig. 3 is a bottom plan view of the device.

I claim:

The ornamental design for a sanitary shield for bottles, as shown.

WILLIAM LAWLOR.
